UNITED STATES PATENT OFFICE

2,106,004

DEVICE USED FOR COATING THE INTERIOR
OF A WATER MAIN

Clinton Inglee, New York, N. Y., assignor to National Water Main Cleaning Co., New York, N. Y., a corporation of New York

Application May 20, 1937, Serial No. 143,636

8 Claims. (Cl. 204—5)

My invention relates to a device for depositing a protective coating on the inner face of metal conduits and particularly to conduits of the type used as water mains.

More particularly this invention pertains to a device of this character, which is adapted to be drawn through a water main, and which in passing deposits the coating on the interior of the latter by means of electrolysis from a colloidal solution or emulsion of fluxed bitumen and other ingredients in an aqueous medium.

It is the purpose of my invention to provide a negatively charged cathode consisting of a flexible spring-like conducting section having longitudinally spaced radially disposed insulated centering springs to support the flexible section and prevent contact thereof with the interior of the conduit, and inflated rubber headers at opposite ends of the cathode to form close contact with the conduit and provide a moving chamber to receive the electrolytic solution and carry it along with the cathode during the electrolytic process.

One embodiment of my invention is described in the following specification, set forth in the appended claims and illustratively exemplified in the accompanying drawing, in which

Figure 1 is a substantially longitudinal sectional view of a straight section of metal conduit with coating apparatus and electrolytic solution therein:

Figure 2 is a substantially longitudinal sectional view of a curved or elbow section of pipe showing the coating apparatus in elevation therein; and

Figure 3 is a substantially transverse sectional view taken on lines 3—3 of Figure 1.

Referring to the drawing, 10 denotes the straight section of water main in Figure 1 and 40 10a the curved section in Figure 2.

The coating or depositing apparatus according to the present invention, comprises a flexible central cylindrical core 11 consisting of a length of helically coiled wire of electrically conducting material, embraced exteriorly at opposite ends and centrally thereof by collars 12 of insulating material. Centering spring arms 13 are attached to each collar 12 and normally flare outwardly and rearwardly to contact the inner face of the conduit and support the core 11 centrally thereof. The rings or collars 12 at opposite ends have each a bail 14, the forward bail receiving a link coupling 15 attached to the trailing end of the cable 16 by means of which the entire apparatus 55 is towed through the main. The rear bail car-

ries a coupling 17 and short link section of cable 18. Both cables 16 and 18 carry and project through rubber headers 19 each of which consists of an inflated bag or cylindrically shaped member having a tubular passage 20 axially thereof to allow the cable to pass through and provide a liquid contact between the wall of the passage 20 and that of the cable. Each header 19 is provided with a valve 21 for inflating and deflating purposes and the leading header accommodates an insulated wire 22 leading from an electric generator (not shown) to the forward end of the flexible conducting core 11. The trailing header is held to its cable 18 by means of a disc 23 against which the header abuts and a nut and washer 24 attaching the disc 23 to the end of the cable.

In operation, the cable 16 is placed in a section of the pipe or water main to be coated interiorly and the forward header 19 is inflated to close the bore of the main beyond the apparatus. The insulated wire 22 provides the negative electrical charge to the flexible core 11 while the conduit or main itself forms the anode. The apparatus is drawn or pulled into the main 10 by means of the cable 16 until the trailing header 19 is just short of entering the main. The electrolytic solution is then fed into the space between the headers until the chamber is full.

The current is applied and the depositing or electrolytic process starts to set up a coating upon the interior wall of the main. This operation continues within the confines of the two headers as the apparatus is pulled slowly through the main.

The advantage of the flexible core cathode resides in its ability to traverse almost any angle without danger of touching the wall of the conduit and causing a short circuit in the line, the central suspension of the core being insured by 40 the centering spring arms 13.

The desirability of confining the coating solutions to the space between the headers will be readily appreciated since it is obvious that the quantity of electrolyte necessary for use in the present apparatus is a great deal less than would be required were the trailing header not used. This is particularly true when the conduit is angular or disposed in the shape of an elbow, in which case the chamber between the headers can 50 be filled with the electrolyte and caused to traverse the conduit in a relatively small quantity, as illustrated in Figure 2. Without this disposition of the headers it would be necessary to practically fill the entire conduit with the solution 55

in order to insure complete deposit entirely over the interior surface.

A further detail of importance in the construction of the present invention resides in the pneumatic headers, which give to these members the desired resiliency necessary to provide an effective seal for the ends of the chamber in which the electrolyte is confined as it traverses the conduit. Under some circumstances the headers may be made of sections of soft or sponge rubber, which would be more or less under compression, while traversing the conduit so as to hold the electrolyte from seeping out of the chamber formed between the two headers.

Having described my invention and the manner in which the same operates, what I claim and desire to secure by Letters Patent is:—

1. An apparatus for electrodepositing a protective coating from an electrolyte on the interior surfaces of metal conduits in which the latter receives a positive electric charge, comprising a negatively charged flexible cathode traversing said conduit, and nonconductive centering means carried by the flexible cathode and supporting the same at spaced intervals between its ends and throughout its length against contact with the conduit.

2. An apparatus for electrodepositing a protective coating from an electrolyte on the interior surface of a metal conduit in which the latter receives a positive electric charge, comprising a negatively charged flexible cathode formed from a length of helically wound conducting material and nonconductive centering members carried by the flexible cathode and supporting the same at spaced intervals between its ends and throughout its length against contact with the conduit.

3. An apparatus for electrodepositing a protective coating from an electrolyte on the interior surface of a metal conduit in which the latter receives a positive electric charge, comprising a negatively charged flexible cylindrical cathode formed of a helically wound wire of conducting material adapted to traverse the interior of said conduit, insulated spring centering devices carried at spaced intervals about said cathode between the ends thereof to prevent contact of the latter with the surface of the conduit and a cable to draw the cathode through the conduit.

4. An apparatus for electrodepositing a protective coating from an electrolyte on the interior surface of a metal conduit in which the latter receives a positive electric charge, comprising a negatively charged flexible cathode traversing said conduit, non-conducting centering means carried by the flexible cathode and supporting the same at spaced intervals between the ends and throughout its length against contact with the conduit and resilient header members under

compression to engage the surface of the conduit at opposite ends of the flexible cathode to confine the electrolytic solution to the space surrounding the cathode during movement of the latter throughout the conduit, each of said headers comprising an inflated rubber bag.

5. An electrodepositing apparatus, as claimed in claim 4, in which each of said inflated rubber bags has a tubular core open at its ends, said apparatus comprising further a link for the trailing end of the cathode projecting through the tubular core of the rear header and being arranged to drag the latter along with the cathode, and a cable connection at the leading end of the apparatus projecting through the tubular core of the leading header and being connected to the forward end of the cathode, the walls of the tubular cores closely embracing the link and cable to form a seal against leakage of the electrolyte solution therethrough.

6. An electrodepositing apparatus, as claimed in claim 1, in which said centering means comprises insulating bands encircling the cathode at spaced intervals throughout its length, spring arms mounted on the bands and projecting rearwardly and radially to yieldably engage and traverse the interior surface of the conduit to center the cathode.

7. An electrodepositing apparatus, as claimed in claim 1, in which said centering means comprises insulating bands encircling the cathode at spaced intervals throughout its length, spring arms mounted on the bands and projecting rearwardly and radially to yieldably engage and traverse the interior surface of the conduit to center the cathode, a bale for each end band, a cable projecting through the forward header and connected to the forward bale whereby the apparatus is drawn through the conduit, a link connection with the rearward bale projecting through the rear header to cause the same to be dragged along with the cathode.

8. An electrodepositing apparatus, as claimed in claim 4, in which each of said inflated rubber bags has a tubular core open at its ends, said apparatus comprising further a link for the trailing end of the cathode projecting through the tubular core of the rear header and being arranged to drag the latter along with the cathode, and a cable connection at the leading end of the apparatus projecting through the tubular core of the leading header and being connected to the forward end of the cathode, the walls of the tubular cores closely embracing the link and cable to form a seal against leakage of the electrolyte solution therethrough, and an insulated wire connected to said cathode and projected through the tubular core of the leading header adjacent the said cable.
